UNITED STATES PATENT OFFICE

150,472

DESIGN FOR A WINDOW VENTILATOR

Verner E. Sprouse, Columbus, Ind.

Application June 19, 1947, Serial No. 139,826

Term of patent 14 years

(Cl. D62—4)

To all whom it may concern:

Be it known that I, Verner E. Sprouse, a citizen of the United States of America, residing at Columbus, in the county of Bartholomew and State of Indiana, have invented a new, original, and ornamental Design for a Window Ventilator, of which the following is a specification, reference being had to the accompanying drawings, forming a part thereof.

Fig. 1 is an inside elevational view of a window ventilator embodying my new design;

Fig. 2 is a top plan view thereof;

Fig. 3 is an outside elevational view thereof; and

Fig. 4 is an end elevational view thereof.

I claim:

The ornamental design for a window ventilator, substantially as shown.

VERNER E. SPROUSE.
